UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,212,500.

Specification of Letters Patent. Patented Jan. 16, 1917.

Application filed February 24, 1915. Serial No. 10,215.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States No. 436,532, to O. Mergenthaler, wherein circulating matrices are released from a magazine in the order in which their characters are to appear in print and then assembled in line, the composed line transferred to the face of a mold, the mold filled with molten metal to 15 form a slug or linotype against the matrices which produce the type characters thereon, and the matrices thereafter elevated and returned through distributing mechanism to the magazine from which they started.

20

25 More particularly, it relates to that class of machines equipped with a plurality of magazines which are movably arranged so that any selected one thereof may be brought into operative relation to the assembling 30 and distributing devices; and its chief object is to provide an improved form of mechanism for effecting this movement of the magazines, as will be more fully described in the detailed description to follow, 35 and finally pointed out in the claims.

40 In the accompanying drawings, I have shown my invention in preferred form and by way of example, and as applied to a linotype machine, but obviously many changes 45 and variations may be made therein, and in its mode of application, which will still be comprised within its spirit. Thus, the details thereof may be widely varied and it may be adapted to other forms of typographical machines, such as typesetters, 50 type-casters and the like, which handle type or dies instead of matrices. Generally speaking, I desire it to be understood that I do not limit myself to any specific form or embodiment, except in so far as such limitations are specified in the claims.

55 Referring to the drawings: Figure 1 is a side elevation of a portion of a linotype machine having my invention applied there-

to; Fig. 2 is a similar view showing the 55 parts in different position; Fig. 3 is a top plan view of the magazine supporting frame; Fig. 4 is a section on the line 4—4 of Fig. 1; Fig. 5 is a section on the line 5—5 of Fig. 1; and Figs. 6, 7 and 8 are detail 60 views.

The matrices X are stored according to font in the magazines A, B and C, which are carried by the shift frame D. The lower magazine C rests directly upon the frame D, 65 while the magazines A and B are mounted upon their customary base frames A¹ and B¹ respectively, which are pivotally connected at their upper ends, as at A² and B², to up-standing projections D¹ of the shift frame, 70 and which rest at their lower ends upon the underlying magazines. The shift frame D is mounted in the supporting frame E, and is arranged so as to be movable toward and from the same to bring one or another 75 of the magazines into operative relation to the assembler entrance G and the channel entrance F¹, which latter is pivoted to the supporting frame E, as at F², and arranged in position to receive the matrices X as they 80 are released from the distributing mechanism F. The parts so far described are or may be substantially similar to those disclosed in my previous Letters Patent No. 1,104,512, dated July 21, 1914. 85

The shift frame D is provided at its forward end with a downwardly projecting plate D³ slidably engaged in a groove or guideway E⁴ in the supporting frame E; and at its rear end the frame D is provided 90 with rollers D², journaled upon the up-standing arms D¹, and traveling upon tracks E¹ rising from the supporting frame. In this way, the frame D is held in position upon the supporting frame E and is properly guided in its shifting movements. The supporting frame E rests at its lower end upon adjusting screws E³ and at its upper end is pivotally mounted upon a pair of supporting studs E² projecting from the 95 framework (see particularly Fig. 5).

100 As previously stated, my present invention relates chiefly to the means for shifting the magazines, and its principal aim is to provide a mechanism which is simple in construction, strong and durable in character, highly efficient in operation, and inexpensive in manufacture. I also propose to

mount such mechanism in the supporting frame E so as to retain all the advantages which exist in such construction, for example, the capability of adaptation to existing machines without material change therein, the easy assemblage of the parts, etc. In carrying out my invention, I employ four rotary cams H, one arranged at each corner of the magazines, and coöperating with 10 rollers D⁴ journaled in arms projecting downwardly from the shift frame D, (see particularly Figs. 4 and 5). The forward pair of cams H is fast upon a transverse rock shaft H² mounted to turn in bearings at the 15 front end of the supporting frame E, while the other pair of cams is fast upon a transverse rock shaft H¹ mounted to turn in bearings at the rear end of the supporting frame. The two shafts are connected by a fore-and-aft shaft H³, which is provided at its opposite ends with bevel gears H⁴ meshing into complementary bevel gears H⁵ fixed to the two shafts H¹ and H² (see Fig. 3). By this 20 construction, the two pairs of cams are caused to rotate in unison so as to shift the magazines to equal extents at their opposite ends. Surrounding the shaft H¹ is a powerful torsional spring H⁶ fixed at one end thereto and at its opposite end to the frame 25 E, and tending to rotate the cam system to raise the magazines and thus to counterbalance their weight.

It will be noted that each of the cams H is formed with two flat surfaces or steps H⁸, upon which the rollers D⁴ rest when one or another of the two lower magazines is in 30 operative position, Fig. 2 showing by full lines the steps at the shorter radii of the cams in engagement with the rollers, and by dotted lines the steps at the longer radii in engagement therewith. When the upper magazine is in operative position, the shift frame D rests upon and is supported by the 35 frame E, as shown in Figs. 1 and 5. In order to prevent the overthrow of the cams at the end of their full range of movement, one of each pair is provided with a lateral 40 projecting lug h which is adapted to engage the supporting frame E at such time.

The operation of the cam system is effected by a handle J (see particularly Fig. 7) fixed to one end of a stub shaft J¹, journaled in the supporting frame E, and which is 45 provided at its opposite end with a small gear J² meshing into a larger gear K¹, fast upon one end of a shaft K. Similarly the shaft K is provided with a small gear K² meshing into a larger gear H⁷ on the end of the shaft H² of the cam system. This 50 arrangement not only enables the operator to shift the magazines uniformly and with little effort, but the gears are so proportioned as to allow the operating handle to 55 occupy the same position after its operation irrespective of the magazine selected, which

feature is important in effecting the proper coöperation of the handle with locking mechanism now to be described.

The handle J (see Fig. 7) is provided with a spring-pressed grip M having a detent M¹, which is adapted to engage in a recess N¹ of a locking plate N² mounted in a block N fixed to the side of the supporting frame E. The block N is formed with a beveled cut N⁷ to engage the detent M¹ and 70 push it outwardly as the handle is rotated so that it may snap automatically into the recess N¹ when it comes into alinement therewith, and the plate N² is formed with a projecting shoulder N⁸ to engage the detent at such time to prevent overthrow of the handle, and thus serve as a locating and registering means therefor. In order to insure that a selected magazine be in proper 75 position, when the handle J is released by the attendant, I construct the locking mechanism so that the handle cannot be engaged therewith at any other time. To this end, the locking plate N² (see particularly Figs. 80 6 and 7) is slidably arranged in the block N and is connected to an arm N³ fixed to one end of a short shaft N⁴, which carries at its other end a spring-pressed arm N⁵ tending normally to shift the locking-plate N² rearwardly, so that its recess N¹ will 85 stand out of alinement with the detent M¹ of the grip M. To control this tendency, I 90 provide the shift frame D with a downwardly extending arm O formed with cam projections O¹, which are adapted to engage a laterally projecting lug N⁶ on the arm N⁵ and cause the latter to shift the locking plate N² back to its active position. There are as many such cam projections O¹ 95 as there are magazines in the frame, and they are so located that they will actuate the arm N⁵ only when one or another of the magazines is brought into operative position. As a result of this construction, if the 100 operator fails to complete the operation of the handle J, it cannot be locked in place (see Fig. 7); but if he does complete its operation, the locking plate N² is shifted to its active position and the detent M¹ will be arrested by the projecting shoulder N⁸ and 105 allowed to snap automatically into the notch N¹ and thus lock the parts against movement 110 (see Figs. 2 and 6). It may be noted that two complete rotations of the handle J are required to effect a change from one magazine to the next one, so that unless the operator completes both these rotations the locking plate N² will remain in inactive 115 position and the handle cannot be engaged in its recess.

Referring to Fig. 8, it will be noted that the back plate of the assembler entrance is connected to the usual supporting frame P by an intermediate bracket P¹, which not 120 only serves as a convenient means of attach- 125

ment, but also as a reinforcing device for the assembler entrance.

As previously stated, I have shown my invention merely in preferred form and by 5 way of example, and it is obvious that many modifications and alterations therein, and in its mode of application, will suggest themselves to those skilled in the art without departure from its scope.

10 Having thus described my invention, its construction and mode of operation, what I claim and desire to secure by Letters Patent of the United States is, as follows:

1. In a typographical machine, the combination of a plurality of magazines, and 15 means for shifting them to bring one or another into operative position, the said means comprising a pair of rotary cams arranged at each end of the magazines and mounted 20 to rotate about a horizontal axis.

2. In a typographical machine, the combination of a plurality of magazines, means 25 for shifting them to bring one or another into operative position, the said means comprising a pair of rotary cams arranged at each end of the magazines and mounted to rotate about a horizontal axis, and connections whereby the several pairs are caused 30 to rotate in unison.

3. In a typographical machine, the combination of a plurality of magazines, a supporting frame sustained by the machine frame, and means for shifting the magazines toward and from the supporting frame 35 to bring one or another into operative position, the said means comprising two pairs of rotary cams journaled in the supporting frame and arranged at opposite ends of the magazines.

4. In a typographical machine, the combination of a plurality of magazines, a supporting frame sustained by the machine frame, and means for shifting the magazines toward and from the supporting frame to 45 bring one or another into operative position, the said means including a system of rotary cams journaled in the supporting frame and arranged at opposite ends of the magazines.

5. In a typographical machine, the combination of a plurality of magazines, two pairs of peripheral segmental cams arranged at the opposite ends of the magazines for shifting them to bring one or another into operative position, and means to prevent overthrow of the cams.

6. In a typographical machine, the combination of a plurality of magazines, and a system of rotary cams for shifting them to 60 bring one or another into operative position, one of said cams being provided with a projecting stud to engage a fixed part of the machine to prevent overthrow.

7. In a typographical machine, the combination of a plurality of magazines, and a 65

system of rotary cams for shifting them to bring one or another into operative position, the said cams being formed with flat surfaces or steps upon which the magazines rest in one position or another.

8. In a typographical machine, the combination of the supporting frame E sustained by the machine frame, the magazine shift frame D movable toward and from the frame E, and means for guiding the frame D in its movements, the said means including the tracks E¹ rising from the frame E at or near its upper end and the rollers D² journaled in the frame D and arranged to travel on the tracks E¹.

9. In a typographical machine, the combination of the supporting frame E sustained by the machine frame, the magazine shift frame D movable toward and from the frame E, and means for guiding the frame D in its movements, the said means comprising the plate D³ projecting downwardly from the frame D and slidably engaged in the groove E⁴ of the frame E, the tracks E¹ rising from the frame E, and the rollers D² journaled in the frame D and traveling on the tracks E¹.

10. In a typographical machine, the combination of a plurality of magazines, a system of rotary cams for shifting them to bring one or another into operative position, transverse rock shafts upon which the cams are mounted, and a torsional spring surrounding one of the shafts and connected at one end thereto and at its opposite end to a fixed part of the machine and serving to counterbalance the weight of the magazines.

11. In a typographical machine, the combination of a plurality of magazines, means for shifting them to bring one or another into operative position, an operating handle therefor adapted to occupy the same position after each of its operations, irrespective of the magazine in use, and automatic mechanism to engage and lock the handle in its operated position.

12. In a typographical machine, the combination of a plurality of magazines, means for shifting them to bring one or another into operative position, and an operating handle for said means adapted to occupy the same position after each of its operations irrespective of the magazine in use, the said handle being provided with a spring-pressed detent adapted to engage automatically in a recess in a part of the machine when the movement of the handle is completed.

13. In a typographical machine, the combination of a plurality of magazines, a pair of rotary cams arranged at each end of the magazines for shifting them to bring one or another into operative position, transverse rock shafts upon which the several pairs of cams are mounted, a fore and aft shaft con-

necting the two rock shafts, an operating handle mounted independently of said fore and aft shaft, and gearing connecting the handle with one of the transverse rock shafts.

14. In a typographical machine, the combination of a plurality of magazines, means for shifting them to bring one or another into operative position, including the rotary shaft H^2 , provided at one end with the relatively large gear H^7 , the operating handle J , a shaft J^1 upon which it is mounted and provided with the relatively small gear J^2 , and the shaft K provided at one end with the relatively large gear K^1 meshing into the gear J^2 and at its opposite end with the relatively small gear K^2 meshing into the gear H^7 .

15. In a typographical machine, the combination of a plurality of magazines, a pair of rotary cams arranged at each end of the magazines for shifting them to bring one or another into operative position, transverse rock shafts upon which the several pairs of cams are mounted, a fore and aft shaft connecting the two rock shafts, an operating handle mounted independently of said fore and aft shaft, and gearing connecting the handle with one of the transverse rock shafts, the said gearing being so proportioned that the operating handle will occupy the same position after each of its operations.

16. In a typographical machine, the combination of a plurality of magazines, a pair of rotary cams arranged at each end of the magazines for shifting them to bring one or another into operative position, transverse rock shafts upon which the several pairs of cams are mounted, a fore and aft shaft connecting the two rock shafts, an operating handle mounted independently of said fore and aft shaft, and gearing connecting the handle with one of the transverse rock shafts, the said gearing being so proportioned that the operating handle will occupy the same position after each of its operations, and locking means to hold the handle in its operated position.

17. In a typographical machine, the combination of a plurality of magazines, means for shifting them to bring one or another into operative position, an operating handle connected to said means and adapted to be rotated a plurality of times to effect a change from one magazine to another, means to engage and lock the handle in its operated position, and means to prevent the locking of the handle unless it has been rotated the requisite number of times.

18. In a typographical machine, the combination of a plurality of magazines, means for shifting the magazines to bring one or another into operative position, an operating handle therefor, a locking device to

engage and hold the handle in its operated position, and means whereby the movement of the magazines controls the action of said locking device.

19. In a typographical machine, the combination of a magazine, means for shifting it to operative and inoperative position alternately, an operating handle therefor, a movable locking device to engage and hold the handle in its operated position, and means whereby the locking device is moved to active and inactive position as the magazine is shifted to operative and inoperative position respectively, for the purpose described.

20. In a typographical machine, the combination of magazine shifting means, an operating handle therefor provided with a spring-actuated detent, and a part of the machine provided with a recess wherein the detent is adapted to engage, the said part being also provided with a projecting shoulder located below the recess to engage the detent and thus secure its registration therewith.

21. In a typographical machine, the combination of magazine shifting means, an operating handle therefor provided with a spring-actuated detent, a locking plate having a recess wherein the detent is adapted to engage, and a part having a beveled cut located in advance of the recess to engage the detent and force it outwardly to permit its subsequent engagement therein.

22. In a typographical machine, the combination of magazine shifting means, an operating handle therefor provided with a spring-actuated detent, a locking plate having a recess wherein the detent is adapted to engage, a part having a beveled cut located in advance of the recess to engage the detent and force it outwardly to permit its subsequent engagement therein, and a projecting shoulder located below the recess to engage the detent and thus secure its registration therewith.

23. In a typographical machine, the combination of magazine shifting means, an operating handle therefor having a spring-actuated detent adapted to engage in a recess in a part of the machine, and means to arrest the detent in alignment with the recess so that it may snap automatically thereinto.

24. In a typographical machine, the combination of a plurality of magazines, means for shifting them to bring one or another into operative position, an operating handle therefor, locking means for said handle, and means to arrest the handle in operative relation to the locking means.

25. In a typographical machine, the combination of a plurality of magazines, means for shifting them to bring one or another into operative position, an operating handle therefor, a device for arresting the handle in

its operated position, locking means to hold the handle in such position, and means whereby the movement of the magazines controls the action of the arresting device.

5 26. In a typographical machine, the combination of a plurality of magazines, means for shifting them to bring one or another into operative position, an operating handle therefor, a movable device for arresting the 10 handle in its operated position, locking means to hold the handle in such position, and means whereby the movement of a selected magazine into and out of operative position effects the movement of the arresting device into and out of active position, respectively.

15 27. In a typographical machine, the combination of a plurality of magazines, a supporting frame distinct from and sustained 20 by the machine frame, and means for shifting the magazines toward and from the supporting frame to bring one or another into operative position, said means comprising a rotary cam system, a pair of rock shafts 25 whereon the cams are mounted and journaled in the supporting frame, and a fore

and aft shaft connecting the two rock shafts and also journaled in the supporting frame.

28. In a typographical machine, the combination of a plurality of magazines, a supporting frame distinct from and sustained 30 by the machine frame, and means for shifting the magazines toward and from the supporting frame to bring one or another into operative position, said means comprising a 35 rotary cam system, a pair of rock shafts whereon the cams are mounted and journaled in the supporting frame, a fore and aft shaft connecting the two rock shafts and also journaled in the supporting frame, an 40 operating handle rotatably mounted in the said supporting frame, and gearing also mounted in the supporting frame and connecting the operating handle with one of the rock shafts.

45 In testimony whereof, I have affixed my signature in presence of two witnesses.

DAVID S. KENNEDY.
